UNITED STATES PATENT OFFICE.

OLUF THESSEN, OF PHILADELPHIA, PENNSYLVANIA.

PUSH-BUTTON SWITCH.

Application filed November 16, 1923, Serial No. 675,114. Renewed June 21, 1927.

My invention relates to a pushbutton switch. The objects are to provide signaling apparatus whereby a soft sound may be produced to warn nearby pedestrians such as are approached at street crossings, and a loud and sharp sound to warn distant pedestrians.

These objects, and other advantageous ends which will be described hereinafter, I attain in the following manner, reference being had to the accompanying drawings in which

Figure 1 is a diagrammatic view of my improved signaling apparatus showing their electrical connections.

Figure 2 a plan view of a push button switch for controlling the apparatus.

Figure 3 a section on line 3—3 of Figure 2, and

Figure 4 as section on line 4—4 of Figure 3.

I have illustrated in the drawings a horn and bell as sound producers for my improved signaling apparatus but any suitable sound producers may be substituted.

Referring to the drawings, the apparatus consists of a source of electrical energy 1 having one of its poles electrically connected to a stationary contact 2; its other pole connected to a bell 3 and a horn 4; a main contact 5 electrically connected to the horn 4 and an auxiliary contact 6 electrically connected to the bell 3. The bell is used for producing a soft sound to warn nearby pedestrians and the horn is used for producing a loud and sharp sound to warn distant pedestrians.

The stationary contact 2 and the movable contacts 5 and 6 are embodied in a switch 7 which may be operated to cut in a circuit to either sound produced. The construction of the switch includes a casing 8 having a groove 9 in its side and an attaching flange 10 at its bottom. The interior of the casing is formed to provide a shoulder 11 near its vertical center and a ledge 12 on the upper edge of the casing. A base 13 of insulating material, abuts shoulder 11 and is held thereby against movement into the casing. The stationary contact 2, as embodied in the switch, is in the form of a strip 14 secured to the base by a screw 15. The strip may be shaped in any suitable manner to serve efficiently as a stationary contact. The movable contact 5 is in the form of a

spring strip 16 secured to the base by a screw 17. A main button 18, slidable in the casing, engages the spring strip 16 and is adapted, when pressed, to move it downward into engagement with strip 14. The edge 19 of the button engages ledge 12 and is thereby held against movement out of the casing. The auxiliary contact 6 is in the form of a spring strip 20 secured to the base by a screw 21. The spring strip 20 consists of an attaching part 22 having a spring arm 23 merging into a contacting lug 24 and having a slot 25 opposite the lug. A groove 26 in the edge of the main button 18 is disposed opposite groove 9 in the casing. An auxiliary push button 27 slides within grooves 26 and 9 and is provided with an annular groove 28 for receiving the edge of slot 25, thus connecting spring strip 20 with auxiliary button 27. The button 27 extends above main button 18 so that it may be pressed inward without pressing button 18. The conduit wires for the contacts 2, 5 and 6 are passed through a cut-out part 29 in the flange and casing and an opening 30 in the base. The proper conduit wire is connected to its contact by a screw in the usual manner.

When the apparatus is used to produce a soft sound, auxiliary button 27 is pressed inward until movable contact 6 engages stationary contact 2. A circuit will then be completed from one pole of source 1 through the bell 3 to the other pole of the source and a soft sound produced. When it is desired to produce a loud and sharp sound to warn distant pedestrians, main button 18 is pressed inward until movable contact 5 engages stationary contact 2. A circuit will then be completed from one of the poles of source 1 through horn 4 and the other pole of the source and a loud sound produced. Thus loud or soft sounds may be produced at the will of the operator to warn nearby or distant pedestrians.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention,

what I claim as new and desire to secure by Letters Patent is:—

1. A push button switch including a casing; an insulating base within the casing; a stationary contact secured to the base; movable contacts secured to the base and adapted to engage the stationary contact; a main button slidable in the casing for moving one of the movable contacts, and an auxiliary button extending above the main button and slidable in a guide channel between the main button and casing for moving the other contact.
2. A push button switch including a casing having a groove; an insulating base within the casing; a stationary contact secured to the base; a main spring contact secured to the base; an auxiliary spring contact secured to the base; a main button, having a groove opposite the groove in the casing, slidable in the casing for moving the main contact into engagement with the stationary contact, and an auxiliary button connected to the auxiliary contact and sliding within the grooves.
3. A push button switch including a casing having a groove; an insulating base within the casing; a stationary contact secured to the base; a main spring contact se-

cured to the base; an auxiliary spring contact secured to the base and having a slot; a main button having a groove opposite the groove in the casing, slidable in the casing for moving the main spring contact into engagement with the stationary contact, and an auxiliary button having an annular groove for receiving the edge of the slot and slidable in the grooves.

4. A push button including a casing having a groove; an insulating base within the casing; a stationary contact secured to the base; a main spring contact secured to the base; an auxiliary spring contact secured to the base and having a slot at its free end; a main button, having a groove opposite the groove in the casing, slidable in the casing for moving the main contact into engagement with the stationary contact, and an auxiliary button slidable within the grooves in the main button and the casing, and having an annular groove fitting over the inner wall of the slot, thereby making a connection with the auxiliary spring whereby it may be moved into engagement with the stationary contact.

In testimony whereof I have signed my name to this specification.

OLUF THESEN.
